CLAIM

The ornamental design for a combined brochure container and dispenser, as shown and described.

DESCRIPTION

FIG. 1 is a top, front, and left side perspective view of a combined brochure container and dispenser showing my new design;

FIG. 2 is a front elevational view thereof;

FIG. 3 is a right side elevational view thereof, the left side being a mirror image of that shown;

FIG. 4 is a top plan view thereof;

FIG. 5 is a rear elevational view thereof;

FIG. 6 is a bottom plan view thereof; and

FIG. 7 is a bottom, front, and right side perspective view thereof.
